UNITED STATES PATENT OFFICE.

WILLIAM MALCOLM BROWN, OF CAMBRIDGE, MASSACHUSETTS.

HOT-WATER BOTTLE.

1,156,054.

Specification of Letters Patent.

Patented Oct. 12, 1915.

Application filed April 11, 1914. Serial No. 831,305.

To all whom it may concern:

Be it known that I, WILLIAM MALCOLM BROWN, a subject of George V, King of England, residing at Cambridge, county of 5 Middlesex, Commonwealth of Massachusetts, have invented certain new and useful Improvements in Hot-Water Bottles, of which the following is a specification.

This invention relates to hot water bottles 10 and particularly to an attachment for localizing the application of the heat of the contained fluid. In hot water bottles as usually constructed, no provision is made for localizing the application of the heat 15 upon the affected part. Where the affected part is inaccessible or where an internal application is desired, it has been practically impossible to get anything like a satisfactory heat application. Where the affected 20 part is accessible but only of comparatively small area it has been necessary in applying the heat to it to cover not only the part affected but also the adjacent parts of the body. This was not only inconvenient and 25 uncomfortable but often resulted in the burning of the portions adjacent the affected part.

To the end therefore of providing an attachment for a hot water bottle which will 30 localize the application of the heat, I have devised my present invention. In it I employ a localizing applicator which may be placed in positive communication with the liquid reservoir of the hot water bottle or 35 may be detached to permit the hot water bottle to be used in the ordinary manner. This localizing applicator is preferably in the form of an auxiliary fluid container of relatively small capacity as compared with 40 that of the main liquid reservoir. Owing to its smaller area the auxiliary container permits a localization and a sustaining of the heat solely upon the affected part and is extremely useful where the affected part 45 is small or inaccessibly located. This container, and preferably the main reservoir also, are flexible so as to permit an interchange of fluid by simple pressure upon one or the other of the containers. This provides for displacing the contained fluid in 50 the localizing container as it cools off and refilling with liquid of higher temperature from the main reservoir.

The construction and principle of my invention will be more fully disclosed in the specification which follows. In the draw-

ings forming a part of that specification, I have shown as an illustrative embodiment a localizing attachment and several forms of connection therefor which I have found satisfactory in practical use. 60

Throughout specification and drawings like reference numerals are correspondingly applied and in these drawings:

Figure 1 is a partial elevation of a hot 65 water bottle equipped with a heat localizing applicator in accordance with my invention, the mouth of the bottle being broken away to illustrate a preferred form of connection between the main liquid reservoir and the 70 applicator. Fig. 2 is an elevation of the localizing container detached. Fig. 3 is a view at right angles to Fig. 2 and showing the container in vertical section. Fig. 4 is an enlarged detail section of the tubular 75 connection shown in Fig. 1 which places the main liquid reservoir and the localizing container in direct communication, and showing a slightly modified form of container. Fig. 5 is a view similar to Fig. 4 of a slightly 80 modified form of connection, and container.

I have indicated at 1 a portion of the main reservoir of a hot water bottle of usual construction. This reservoir is preferably of some flexible material as rubber with water-proofed seams and with or without a fabric protective covering, although obviously this container could be of metal. In the form shown it is an ordinary rubber bag having a neck 2 and an outwardly flared mouth 3. 90 The neck 2 is lined with an internally threaded sleeve 4 into which, when the device is used as an ordinary hot water bottle, a threaded stopper (not shown) is adapted to be threaded to close the delivery opening. 95 When it is desired to localize the heat application, an externally threaded tubular connecting member 5 is threaded into the sleeve 4. This connection places the reservoir 1 into direct communication with a localizing 100 applicator which is preferably in the form of a relatively small fluid container 15 having detachable engagement with the member 5 by means of its depending nipple 14 and beaded extension 13 on said connecting member. The connection 5 is provided with a key 6 adapted to be grasped between the thumb and forefinger to thread the member 5 into and out of the sleeve 4. The key 6 is normally disposed within the flared mouth 110 3 when the member 5 is screwed home. (See Fig. 1.)

In order to make the connection 5 positively water tight at the delivery opening of the container 1 the lower end of this member is turned in at 7 to provide a flat 5 annular seat, then downwardly as indicated at 8 and finally back outwardly upon itself as indicated at 8¹. These bends define an annular recess in which is inserted and clamped a compressible joint in the form of 10 a rubber gasket 9 and a superimposed metallic washer 10. This form of joint is obviously capable of variation however, and in Fig. 5 I have shown a slight modification. In that form the lower end of the member 15 5 is turned in at 7 and down at 8, as in the form illustrated in Fig. 4. The flange 8 is not bent back upon itself however but instead terminates abruptly as shown. A flanged tube or grommet 12 is inserted in 20 the delivery opening of the member 5 and finds bearing against the bottom edge of the flange 8. The upper end of the tube 12 has an outward flare and lies snugly against the inner face of the flange 8, being compressed 25 down onto the seat 7 so as not to be detachable from the member 5. In the annular recess defined by the portions 7 and 8 and the flange 12¹ of the tube 12 are seated and clamped a rubber gasket 9 and a metallic 30 washer 10, as in Fig. 4.

The connection 5 is formed at its opposite end with a hollow restricted extension 13 having a bead over which fits the depending nipple 14 of the localizing container 15. This container 15 is of relatively 35 small area and capacity as compared with the main reservoir 1. It is placed in direct communication with said reservoir by the hollow connecting member 5. The container 40 15 may be of any desired material but is preferably of rubber having an insulating covering piece 16 on one side so as to prevent burning of the body from an application of too intense heat. The container 15 45 presents a localized and sustainable application of heat and being of considerably smaller area than the container 1 is capable of application in many places where the container 1 could not be used.

50 When the temperature of the water in the localizing container lowers it is often desirable to replace it with water of a higher temperature. The water which has cooled off in the container 15 may be displaced and 55 returned to the main reservoir by a simple pressure on either container. This pressure is effective to partially empty the container and cause a partial interchange of the container fluid from one reservoir to the other.

60 In use, when it is desired to localize the

heat application the connection 5 is screwed home into the sleeve 4 until the rubber gasket 9 seats on the seat provided by the in-turned flange 17 on the lower end of the sleeve 4. The contained fluid in the reservoir 1 is now free to flow into the smaller container 15 through the passage afforded by the tubular connection 5. When it is desired to use the device as an ordinary hot water bottle the member 5 is unscrewed and 65 an ordinary stopper is threaded into the sleeve 4.

Various modifications in the form, size and material of the containers 1 and 15 and in the type of connection 5 between said containers may obviously be resorted to within 75 the limits of the appended claims.

What I therefore claim and desire to secure by Letters Patent is:

1. A thermal applicator comprising a local reservoir of limited capacity and a main reservoir of thermally dominating capacity, each reservoir constructed to form an applicator, said reservoirs being in communication and said main reservoir including a 80 discharging element operative to effect an interchange of content between said local and said main reservoirs.

2. A thermal applicator comprising a local reservoir of limited capacity and a main 90 reservoir of thermally dominating capacity, each reservoir constructed to form an applicator, said reservoirs being in communication and said main reservoir including a compressible wall effective to merge the content of the local reservoir in the content of the main reservoir and recharge said local reservoir with a new charge of the thermal character of said main reservoir content.

3. A thermal applicator comprising a local reservoir of limited capacity having a communicating opening and a main reservoir of thermally dominating capacity having a filling opening, each reservoir constructed to form an applicator, and a coupling member having detachable engagement in said openings for placing said reservoirs in communication, said main reservoir being compressible to permit the content of the local reservoir to be merged in 100 the content of the main reservoir and said local reservoir to be recharged with a new charge of the thermal character of said main reservoir content.

In testimony whereof I affix my signature 115 in presence of two witnesses.

WILLIAM MALCOLM BROWN.
